UNITED STATES PATENT OFFICE.

THOMAS R. LEWIS, OF JERSEY CITY, NEW JERSEY.

DESIGN FOR A MITT.

Application filed March 3, 1923. Serial No. 5,351. Term of patent 3½ years.

To all whom it may concern:

Be it known that I, THOMAS R. LEWIS, bodying my design, a citizen of the United States, residing at Jersey City, in the county of Hudson and State of New Jersey, have invented a new, original, and ornamental Design for Mitts, of which the following is a specification, reference being had to the accompanying drawing forming a part thereof.

Figure 1 is an elevation of a mitt embodying my design.

Fig. 2 is an obverse view.

I claim:

The ornamental design for a mitt, as shown.

THOMAS R. LEWIS.
